UNITED STATES PATENT OFFICE.

ALEXANDER LAUBSCHER, OF BRIDGEPORT, CONNECTICUT, ASSIGNOR TO WHEELER & WILSON MANUFACTURING COMPANY, OF BRIDGEPORT, CONNECTICUT, A CORPORATION OF CONNECTICUT.

HEM-FOLDER FOR SEWING-MACHINES.

SPECIFICATION forming part of Letters Patent No. 723,615, dated March 24, 1903.

Application filed May 12, 1902. Serial No. 106,996. (No model.)

To all whom it may concern:

Be it known that I, ALEXANDER LAUBSCHER, a citizen of the United States, residing at Bridgeport, in the county of Fairfield and State of Connecticut, have invented a certain new and useful Improvement in Hem-Folders for Sewing-Machines, of which the following is a full, clear, and exact description.

This invention relates to hem-folders for sewing-machines, and more particularly to that class of folders employed for hemstitching.

The object of the invention is to provide adjustable means for controlling the width of the edge or seam fold as distinguished from and in addition to means for controlling the width of the fold or hem proper.

Hem-folders as commonly constructed are provided with adjustable means for varying the width of the hem between the line of seam and the turn or fold forming the outer edge of the material operated upon, while the width of the edge or seam fold or that portion of the goods turned in at the sewing-line is of a single gage, dependent upon the construction of the folder. In the improved device herein shown and described the folder is provided with an independent adjustable gage, whereby may be produced wide or narrow seam folds, dependent upon the nature of the material being operated upon.

It is well understood that an open or coarse weave demands a wider hem to insure substantial service than does a close fine weave, and the same is true in the matter of weight of material. A much narrower hem can be employed on fine cambric, such as is used in handkerchiefs, than on coarse heavy muslins, such as are commonly used in the manufacture of the low grades of sheets and pillow-cases.

By this invention is provided a single attachment for making both folds which meets the requirements of fabrics of different texture or weave.

In the accompanying drawings, illustrating the invention, in the several figures of which like parts are similarly designated, Figure 1 is a plan view. Fig. 2 is a front elevation.

Fig. 3 is a perspective view of the adjustable gage for effecting a variation in the width of the edge or seam fold. Fig. 4 is a perspective view of the folder-tongue, which coacts with the left-hand folder to form the seam fold.

In the drawings one known form of hem-folder is shown, to which the invention is applied, and, briefly, said known folder comprises a base-plate 1, adapted to be secured by a pivot-screw 2 and stop-pin 3 to the bed-plate of a sewing-machine and displaceably held in place by a spring 4.

5 is a bracket applied to the plate 1 and in turn supporting a bracket 6, upon which is mounted an arm 7, from which projects a finger 8, to which is secured one of the folders 9. From this arm also projects a plate 10, which is practically an extension of the folder 9. An arm 11 is adjustably secured to the bracket 6 by means of a slot 12 and set-screw 7c 13, and this arm 11 has a finger 14, which supports the other folder 15, the said folder 15 having an extension 16, which constitutes a support for the passing fabric:

17 is a plate attached by screws 18 to the arm 11 and extending as a tongue to the outer end of the folder 15, as shown in dotted lines, Fig. 1, and also extending in the opposite direction as a support for the fabric.

The tongue 19 varies from prior constructions in being somewhat wider, and said tongue has a wall 20, by which it is attached to arm 7 by means of screws 21. Above the plane of the tongue 19 the arm 7 is provided with a slot 22, and a sliding plate 23 is mounted upon the arm 7 above said slot and is itself provided with a longitudinal slot 24 and a set-screw 25, by means of which it may be adjusted longitudinally of the said arm. As shown more particularly in Fig. 3, this plate 23 has a right-angle projection 26 depending from it, and said projection is provided with an inclined end 27 and a lip 28, so as to conform substantially to the vertical and horizontal walls, respectively, of the tongue 19, 95 and said projection is arranged within the tongue and parallel with its walls, and by means of the slots 22 and 24 and set-screw 25

the said device is adjustable toward and from the vertical wall 20 of the tongue, and thus becomes, in effect, the gage hereinbefore referred to as the means for permitting an operator to vary the width of the fold or turn of the fabric at the line of stitching in accordance with the texture or weave of the fabric being sewed.

Heretofore in this class of devices the wall 20 of the tongue was the medium by which the hem or seam fold was effected, and inasmuch as it was fixed of course no variation in the width of such fold or turn could be effected; but by the application of the adjustable gage of this invention such variation may be readily effected entirely independently of the adjustment of the folders toward and from one another for varying the width of the fold or hem proper.

It will be understood that by loosening the set-screw 13 the folder 15 may be adjusted toward and from the folder 9 to permit variation in the width of the hem proper and that this adjustment of the folders is entirely independent of the adjustment of the gage last

described for effecting a variation in the seam fold.

What I claim is—

1. A hem-folder, provided with means for controlling the width of the fold or hem proper, 30 an independent gage for the seam fold, and means to adjust said gage to vary the width of the said seam fold.

2. A hem-folder, for sewing-machines, provided with adjustable means for varying the 35 width of the hem from seam to outer edge, and an independent gage adjustable relatively to the folders to vary the width of the seam fold.

3. In a hem-folder, for sewing-machines, 40 adjustable folders, a tongue in one of said folders, and an independently - adjustable gage arranged in said tongue, for effecting a variation in the width of the seam fold.

In testimony whereof I have hereunto set 45 my hand this 10th day of May, A. D. 1902.

ALEXANDER LAUBSCHER.
